UNITED STATES PATENT OFFICE.

SALVATORE SCOGNAMILLO, OF NEW YORK, N. Y.

AUTOMOBILE VIBRATING HORN.

1,209,629.

Patented Dec. 19, 1916.

Specification of Letters Patent. Application filed July 1, 1915. Serial No. 37,565.

To all whom it may concern:

Be it known that I, SALVATORE SCOGNAMILLO, a citizen of the United States, residing at New York, in the county of New York and State of New York, have invented new and useful Improvements in Automobile Vibrating Horns, of which the following is a specification.

This invention relates to an automobile horn or alarm signal of the vibrating or percussing type; and one object of the same is to provide a horn of this character embodying a simplified construction which is exceptionally cheap in the cost of manufacture, yet effective in its operation to produce a strong alarm sound.

With this and other objects and advantages in view the invention consists in the construction and arrangement of the several parts which will be more fully hereinafter described and claimed.

In the drawing: Figure 1 is a sectional elevation of a vibrating or percussing horn embodying the features of the invention. Fig. 2 is a transverse vertical section taken in the plane of the line 2—2, Fig. 1.

The numeral 5 designates a casing suitably struck up in cup shape as shown to form a practical inclosure and having a front flange 6. A simple form of resonator 7 is also provided and formed with a securing flange 8 which is attached to the flange 6 by suitable rivets or other analogous fastenings 9. Between the flanges 6 and 8 respectively of the casing and the resonator, a diaphragm 10 is held by the fastenings 9, and at its center this diaphragm has a projection 11 extending rearwardly therefrom and is preferably the blunt point of a screw 12 which is supported in the diaphragm by a washer disk 13 secured on the front of the diaphragm and a rear disk 14. The disks 13 and 14 may be of insulating material, and particularly the disk 14. The rear side 15 of the casing 5 has upper and lower binding posts 16 and 17 secured thereto, and to these posts wires 18 and 19 are respectively connected and form part of a battery circuit which includes as usual a push-button or analogous circuit closing means. The upper binding post 16 is fully insulated from the rear side 15 of the casing 5, and the lower binding post 17 is in metallic connection with said rear side of the casing. At the center of the rear side 15 of the casing and in metallic connection therewith is an adjusting screw 21 having its point 22 pro-

jected into the case and serving as one contact of a circuit breaker. The active or operating part of the improved horn or the essential actuating means is organized in one structure and when applied in the casing all the members thereof will be in proper operating position, the said essential actuating organization comprising an elongated spring 23 which is secured between the upper portion of the diaphragm 10 and the flange 6 of the casing 5. The spring 23 has an electro-magnet 24 secured thereto, a contact or impacting button or disk 25 being mounted on the spring 23 in line with the point of attachment thereto of the electro-magnet, said impacting button or disk 25 being in line with the projection 11 and formed of metal. Secured to the lower end of the spring is an insulating connector 26 having a spring arm 27 fixed to its rear end and extending upwardly and provided with a terminal armature 28, which in the present instance is in the form of a metal plate bent over and secured to the upper end of the spring in line with the pole 29 of the magnet 24. The armature 28 carries a contact 30 which normally engages the contact 22 or the point of the screw 21. The one terminal of the winding of the electro-magnet is connected by a wire 31 to the binding post 16 and the other or opposite terminal of said winding is connected by a wire 32 to the spring arm 27.

It will be observed that the spring 23 carries the electro-magnet 24, spring arm 27 and armature 28 in suspended relation within the casing 5, and the several parts of this actuating mechanism can be simultaneously installed or placed in operative position within the casing at a very small cost and without requiring any accurate adjustment, it being proposed to so primarily proportion and arrange the parts that a quick operative assemblage may be obtained by simply securing the spring 23 to the upper portion of the casing, as hereinbefore explained, when the impacting button or disk 25 and armature 28 with the contact 30 will be in proper position relatively to the projection 11 and the contact 22. When the circuit including the wires 18 and 19 is closed, the said circuit being from the binding post 16 by wire 31 through the electro-magnet 24, over wire 32 to the spring 27, from spring 27 by way of the contact 30 to the screw 21, and from the screw 21 through the rear side or back 15 of the casing 5 to the binding post 17 and out through the wire 19. When the circuit is

thus closed the electro-magnet 24 becomes energized and attracts the armature 28, and at the same time the impacting button or disk 25 is drawn toward the projection 11 owing to the magnetism that is set up.

As soon as the armature 28 is drawn toward the pole of the electro-magnet the engagement between the contacts 22 and 30 is broken and a release is effected by reason of 10 the broken circuit and the parts returned to their normal position as shown by Fig. 1, and immediately the circuit is again made and an impact between the button or disk 25 and the projection 11 ensues. This vibration and successive impact between the disk 15 or button 25 and the projection 11 takes place very rapidly while the circuit including the wires 18 and 19 is closed, and a practical alarm signal is emitted through the 20 resonator 7.

The improved device as a whole is exceptionally advantageous, particularly from a commercial standpoint or in the cost of manufacture and may be produced and 25 placed upon the market at a materially reduced price.

What is claimed is:

1. In an automobile horn of the class specified, the combination of a casing, a 30 resonator secured thereto, a diaphragm between the casing and resonator provided with a rear projection at the center thereof, a main suspending and carrying spring secured to the upper portion of the casing within the 35 latter and having an electro-magnet attached to the rear side thereof and an impacting disk at the front side of the spring in line with the projection of the diaphragm, an insulating connector secured to and projecting 40 from the free end of the said main spring, an upwardly extending spring arm secured to the insulating connector and spaced from the said main spring and provided with an armature at its upper free end in operative 45 adjacency to the pole of the magnet, the armature also carrying a contact projection, a contact adjustably mounted in the rear of the casing and normally in engagement with the contact on the armature, and electrical 50 connections for the electro-magnet and armature whereby when the circuit is closed a vibration of the main spring will be set up by the action of the magnet and the armature to effect a rapid impact of the 55 disk on the said latter spring with the projection on the diaphragm.

2. In an automobile horn of the class specified, a casing, a resonator, a diaphragm held between the casing and resonator 60 and provided with a rearwardly extending projection, a vibrating organization suspended within the casing in rear of the diaphragm and comprising an elongated main

suspending and carrying spring with an impacting disk to engage the projection of 6 the diaphragm, an electro-magnet secured to and movable with said main spring, and a yieldingly supported armature secured to the lower end of and spaced from the said main spring in rear of the electro-magnet 70 and carrying a contact forming part of a circuit breaker, a contact held by the rear portion of the casing and normally in engagement with the contact on the armature and completing the circuit breaker, and 75 electrical connections for the electro-magnet and armature.

3. In an automobile horn of the class specified, a casing, a resonator, a diaphragm held between the casing and resonator and 80 having a projection, a main carrying spring depending into the casing and having an impacting disk to engage the projection on the diaphragm and also provided with an electro-magnet, and a yieldingly supported 85 armature in rear of the magnet and connected to the free end of the main spring and carrying a contact to form part of the circuit breaker, the spring with the electro-magnet and armature all regularly vibrat- 90 ing as a unit within the casing, the armature being insulated from the said main spring, a circuit breaking contact carried by the casing and normally engaging the contact of the armature, and electrical connections for 95 the electro-magnet and armature.

4. In an automobile horn of the class specified, a casing, a resonator, a diaphragm between the casing and resonator, a magnetic vibrating means suspended within the 100 casing and comprising a main spring arm carrying an electro-magnet and an impacting device to engage a portion of the dia- 105 phragm and a supplemental spring arm disposed in rear of and projecting upwardly parallel to said main spring arm and carrying an armature in rear of the electro-magnet, said supplemental spring arm being insulated from the main spring arm, a circuit breaker in part carried by the casing and 110 the said armature, and electrical connections for the electro-magnet and armature, the main spring arm, supplemental spring arm, electro-magnet and armature all vibrating bodily by the action of the electro-magnet 115 on the armature to cause the impacting device on the main spring arm to strike a portion of the diaphragm.

In testimony whereof I have hereunto set my hand in presence of two subscribing 120 witnesses.

SALVATORE SCOGNAMILLO.
